UNITED STATES PATENT OFFICE.

HARRY W. LAWRENCE, OF DENVER, COLORADO.

SINGLE-PIECE SHELL FOR ELECTRIC-LIGHT SOCKETS.

1,150,275.

Specification of Letters Patent. Patented Aug. 17, 1915.

Application filed May 12, 1914. Serial No. 838,093.

To all whom it may concern:

Be it known that I, HARRY W. LAWRENCE, a citizen of the United States of America, residing in the city and county of Denver and State of Colorado, have invented a new and useful Single-Piece Shell for Electric-Light Sockets, of which the following is a specification.

My invention is for a single piece shell for electric light sockets, and the objects of my invention are: First. To provide in a socket shell an undivided single piece integrally constructed shell of any shape or design. Second. To provide in a socket shell, a shell that is so arranged that a switch key can be used with it that is made separate from the switch mechanism and that can be applied through a key hole formed in the shell to manipulate the switch mechanism, to turn on or off the light. Third. To provide in a socket shell, a shell that is adapted by means of a key hole, to lock itself to the switch mechanism of the socket. I attain these objects by the mechanism illustrated in the accompanying drawings, in which:

Figure 1 is a side elevation of the improved shell for electric light sockets. Fig. 2 is a vertical sectional view of the same, showing more clearly the guide groove leading from the mouth of the socket to the key hole aperture; and Fig. 3 is a horizontal sectional view on the line 3—3 of Fig. 1.

Similar letters of reference refer to similar parts throughout the several views.

I have illustrated a round shell of a particular design, but my invention contemplates any new type of socket shell made in any suitable shape of cross section and of any design and character of artistic and decorative embellishment.

In the drawings the numeral 1 designates, in general, a socket shell embodying my invention. It consists of a single integral piece of any material suitable to be used in the construction of shells for use in electric light sockets. I preferably, however, make these shells out of insulating material and preferably make them out of porcelain in the manner well understood in the art of making porcelain articles. My improved shell can be made, however, of thin brass or any other suitable metal, but when metal is used the shell should be provided with an insulating lining of fiber or other suitable insulating material. I do not illustrate this

lining, as it does not form any part of my present invention.

My improved shell for electric light sockets comprises a single casting of porcelain or other insulating material, or a single piece of brass or other suitable metal. In either case it is made in one integrally whole and undivided monolithic member and structure, having a large axial aperture 2, 60 extending into one end of it for most of its length and large enough to receive the switch mechanism and its supporting casing, which I do not illustrate as it does not form any part of my present invention. 65

My improved single piece shell is provided with a keyhole aperture 3, and I also preferably provide the inner wall of the shell with a keyway recess 5. This feature may, however, if desired, be dispensed with. 70

The opposite end of the shell from its switch casing receiving end is provided with an axial aperture 6, that connects with the large axial aperture that extends into it from its opposite end, and this smaller aperture 6, is adapted to receive the circuit wires that lead to the switch mechanism. The outside surface of the shell is also provided with a raised lug portion 7 around the key-hole aperture, which is adapted to act as a 85 reinforcement of the shell around the key-hole. This feature is an essential object in thin shells, but if desired can be dispensed with in thick shells. My invention contemplates its use or not, as well as the use or 90 not of the keyway recess 5, as desired.

My improved shell may be made of any shape or form, and its outside surface may be provided with any suitable arrangement of beads, moldings or parts in relief, or 95 other characters of artistic decorative elements. I have illustrated it made up in a simple but artistic arrangement, which comprises a dome shaped portion 8 at the cord receiving end of the shell that tapers pointedly to a slight projecting axially arranged lug portion, through which the circuit wires receiving aperture is formed. Below the dome portion the body 9 of the shell is reduced in diameter, and at its opposite end a 100 raised bead is formed around it and another bead is extended around it at a short distance from the end bead. The keyhole reinforcing raised lug is formed on the body portion and extends to the adjacent edge of 110 the hood portion.

I do not wish to be limited to the design

of the shell or to the decorative and artistic arrangement of its outside surface as illustrated, as my invention contemplates any artistic and decorative arrangement of the 5 outside surface of the shell desired.

When the shell has been made in one whole undivided integral piece with the key hole aperture formed through it into its large axial aperture in position to allow a 10 key to operate the switch mechanism, it is complete and ready for use and to receive the switch mechanism, and after it is so made it is entirely free from additional pieces or parts and does not have connected 15 to it any screws or clips, but is ready as illustrated in Fig. 1, to receive the switch, the switch mechanism and its supporting casing.

I do not illustrate the separate key that 20 the key hole aperture of my shell is made to receive and that it is necessary to insert through the key hole in order to manipulate the switch mechanism to turn on or off the light, and I do not illustrate the switch 25 mechanism and its coöperating mechanism that enables the key to properly connect

with it and that enables the shell to become automatically locked to it, it being sufficient to say that the key is applied to the key hole and that an element of the switch 30 mechanism extends up into the key hole and receives the key, as these features are embodied in a separate application Ser. No. 838,092, executed simultaneously with this application and filed in the Patent Office at 35 the same time with this present application.

Having described my invention, what I claim as new and desire to secure by Letters Patent is:

A lamp socket, comprising an integral 40 shell having a keyhole and an interior groove extending from the socket opening to said keyhole, said groove providing a guide-way for the switch-operating means during the assembling of the parts.

In testimony whereof I affix my signature in presence of two witnesses.

HARRY W. LAWRENCE.
